UNITED STATES PATENT OFFICE

171,555

FLOOR TYPE AIR CIRCULATOR

Robert Podall, Chicago, Ill., assignor to Berns Manufacturing Corporation, Chicago, Ill., a corporation of Illinois

Application April 27, 1953, Serial No. 24,691

Term of patent 14 years

(Cl. D26—7)

To all whom it may concern:

Be it known that I, Robert Podall, a citizen of the United States, residing at Chicago, Cook County, Illinois have invented a new, original, and ornamental Design for a Floor Type Air Circulator, of which the following is a specification, reference being had to the accompanying drawing, forming a part hereof:

Fig. 1 is a perspective view of a floor type air circulator, embodying my new design;

Fig. 2 is a top plan view of the same; and

Fig. 3 is a side elevational view of the same, all sides being identical in appearance.

Figs. 2 and 3 are on a reduced scale for the convenience of illustration.

I claim:

The ornamental design for a floor type air circulator, substantially as shown and described.

ROBERT PODALL.
